DESIGN FOR A PIN BROOCH OR THE LIKE

Irving Geist, New York, N. Y.

Application December 16, 1940, Serial No. 97,392

Term of patent 3½ years

To all whom it may concern:

Be it known that I, Irving Geist, a citizen of the United States, residing in New York city, in the county of New York and State of New York, have invented a new, original, and ornamental Design for a Pin Brooch or the like, of which the following is a specification, reference being had to the accompanying drawing, forming part thereof.

Fig. 1 is a plan view of a pin brooch or the like showing my new design.

Fig. 2 is the reverse side of Fig. 1, and Fig. 3 is a side elevational view thereof.

While I have shown my design embodied in a pin brooch, it is contemplated that the same may also be embodied in similar articles of jewelry without departing from the spirit of my invention.

I claim:

The ornamental design for a pin brooch or the like, substantially as shown and described.

IRVING GEIST.
